UNITED STATES PATENT OFFICE.

ALBERT F. FULLER, OF NEWARK, NEW JERSEY, ASSIGNOR TO THE J. E. MERGOTT COMPANY, OF NEW JERSEY.

PURSE OR BAG FRAME.

SPECIFICATION forming part of Letters Patent No. 661,579, dated November 13, 1900.

Application filed September 21, 1900. Serial No. 30,668. (No model.)

To all whom it may concern:

Be it known that I, ALBERT F. FULLER, a citizen of the United States, residing at Newark, in the county of Essex and State of New Jersey, have invented certain new and useful Improvements in Purse or Bag Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in bag or purse frames and catches therefor; and the invention refers more especially to that class of frames employed with chatelaine-bags and belt-bags, but may also be used with any other known construction of bag.

This invention has for its primary object to provide a simple and neat construction of holding or locking catch for bag or purse frames which is of a strong and durable construction, securely retains the frame-sections of the bag or purse in their closed relation to each other, and is readily manipulated when used in connection with chatelaine or belt bags by means of a simple push or pressure in a downward direction against a finger-piece of the holding or locking catch, whereby the bag or purse can be opened by means of one hand.

The invention has for its further object to provide a novel means for securing the frame-sections to a side piece of a bag and an auxiliary and smaller bag which forms a pocket on the side of the large bag.

My invention therefore consists in the novel construction of bag or purse frame hereinabove fully set forth and in the novel construction of a holding or locking catch therefor.

This invention consists, furthermore, in the several novel arrangements and combinations of the various parts, as well as in the details of the construction thereof, all of which will be hereinafter fully described and then embodied in the clauses of the claim which forms a part of this specification.

The invention is clearly illustrated in the accompanying drawings, in which—

Figure 1 is a side view of part of a side piece of any suitable form of bag provided with a side pocket, said view illustrating in connection therewith in side view one form of bag or purse frame and holding or locking catch embodying the principles of my present invention. Fig. 2 is a rear view of a portion of the said side piece of the bag and its pocket, illustrating one means of securing the frame thereto. Fig. 3 is a vertical section of the several parts represented in said Figs. 1 and 2, said section being taken on line 3 3 in said Fig. 1. Fig. 4 is a top edge view of the two frame-sections and catch. Fig. 5 is a bottom view of the same, and Fig. 6 is a horizontal section taken on line 6 6 in Fig. 1. Fig. 7 is a vertical cross-section, on an enlarged scale, of the two frame-sections and the holding or locking catch, illustrating the several parts in their held or locked engagement, said section being taken on line 7 7 in Fig. 4. Fig. 8 is a similar section of the parts represented in said Fig. 7, but illustrating the holding or locking catch in its actuated or raised position to permit the frame-sections of the purse or bag frame to be opened; and Fig. 9 is a longitudinal vertical section of one of the frame-sections, the holding or locking catch therefor, and the casing in which said holding or locking catch is arranged, said section being taken on line 9 9 in said Fig. 4. Fig. 10 is a perspective view of the holding or locking catch and its finger-piece when viewed from the bottom.

Similar letters of reference are employed in all of the said above-described views to indicate corresponding parts.

In the said drawings, *a* indicates the usual side piece of any suitable construction of bag, which is made of leather, and *b* is a suitable bag which is secured beneath the opening *a'* in said side piece *a* by means of my novel construction of frame and forms an auxiliary bag or pocket to the large bag, of which *a* is one of the side pieces.

In the present construction of frame, *c* indicates a $\square$ -shaped frame-section which is provided at its lower end portions *c'* with a

pair of forwardly-projecting lugs or ears c^2 , in each one of which there is a suitable hole or perforation for the purposes hereinafter specified. The outer marginal edge of said frame-section c may be scalloped or ornamented in any other desirable manner, and on its outer face, contiguous to said marginal edge, this frame-section c may be provided with a raised portion c^3 . This raised portion c^3 is made to conform with the outer configuration of the said frame-section c and is preferably made separate therefrom, as shown; but this is not essential, and the said portion c^3 may be entirely omitted, if desired. When the frame-section c and portion c^3 are to be attached around the opening a' in the side piece a and around the mouth of the bag b , the said parts are provided with suitably-disposed holes or perforations, in which are arranged pins or rivets d , which are passed through the material of the bag parts a and b and through correspondingly-arranged holes or perforations in a holding strip or section d' upon the back of the bag b and clenched to provide heads on said pins for securing the said parts firmly together in the manner illustrated in said Figs. 1, 2, and 3 of the drawings.

Pivotal secured against the flat face or surface of the frame-section c is the other frame-section e of the bag or purse frame. This frame-section e is also made L -shaped when viewed from the front, and in cross-section is Γ -shaped. The lower end portions e' of the said frame-section e are provided with suitably-arranged holes or perforations and are pivotally connected with the ears or lugs c^2 of the frame-section c by means of pins or rivets f . The said frame-section e is secured upon the surrounding portion a^2 of the side piece a and the mouth portion b' of the auxiliary bag or pocket b by means of an ordinary inlay h and rivets or pins i , as clearly illustrated in the several figures of the drawings.

The arrangement and construction of the holding or locking catch and its casing are as follows: The casing, as will be seen more especially from Figs. 7, 8, and 9, consists, essentially, of a bent or curved top l and the front l' and back l'' , the said curved top l being provided at its ends with lugs l^3 , which are passed through holes or openings e^5 in the part e^4 of the frame-section e and then bent over against the under side of the said parts e^4 to secure said casing l in place, as will be clearly evident from Fig. 9. In the front piece l' of the said casing l is an opening l^4 , and the back piece l'' of said casing is provided with an oppositely-placed hole or opening l^5 . Within this casing l I have arranged the main portion of a holding or locking catch l^6 , the same having a forwardly-extending portion l^7 , which projects from the opening l^4 in the front piece l' of the casing l and is provided with an upwardly-bent and forwardly-projecting finger-piece l^8 , substantially as illustrated. The said main portion

of the holding or locking catch l^6 is also provided with a rearwardly-extending portion l^9 , which projects from the opening l^5 in the back piece l'' of said casing l . The said main portion of the holding or locking catch l^6 is retained in its normal position (indicated in Figs. 6, 7, and 9) by means of a pair of oppositely-arranged lugs or projections l^{11} , which are placed between the inner surfaces of the front and back walls of the casing l to prevent lateral displacement, and also by means of a flat spring o , which is placed over the main portion of the holding or locking catch l^6 and has its ends o' in forcible engagement with the under surface of the curved top l , as clearly illustrated in said Fig. 9. Thus it will be seen that when there is no pressure or force exerted against the finger-piece l^8 the tendency of said spring o is to retain the holding or locking catch in the position illustrated more particularly in Fig. 7, thereby permitting when the frame-section e is closed against the frame-section c a nosing or holding jaw l^{10} on the rearwardly-extending portion l^9 to be passed through an opening c^4 in said frame-section c and engage with the edge c^5 just below said opening c^4 to retain the frame-sections in their locked relation to each other.

To free the two frame-sections from their relatively-locked engagement, a slight push or pressure is exerted from the hand of the person wearing the chatelaine-bag suspended from a belt against the curved portion l^{12} of the finger-piece l^8 , thereby lifting the nosing or holding jaw l^{10} from its holding engagement with the edge c^5 of the frame-section, the curved end portion l^7 acting as a fulcrum against the upper surface e^2 of the frame-section e , as clearly indicated in Fig. 8, and the two frame-sections c and e can then be opened, as clearly indicated in Fig. 3.

Although I have described my novel construction of purse or bag frame and its holding-catch in connection with a side piece, as a , of a bag and a pocket b therein, it will be understood that I may employ the herein-described frame construction and the locking or holding catch in the ordinary manner of frames for the usual forms of bags or purses.

I am aware that changes may be made in the several arrangements and combinations of the various parts, as well as in the details of the construction thereof, without departing from the scope of my present invention. Hence I do not limit my invention to the exact arrangements and combinations of the parts as herein shown and described, nor do I confine myself to the exact details of the construction thereof.

Having thus described my invention, what I claim is—

1. In a bag or purse frame, the combination, with a pair of hinged or pivoted frame-sections, of a lock or catch on one of said frame-sections, comprising, a casing secured upon the frame-section, provided with a front and back piece, each piece having an opening

therein, and a spring-actuated holding or locking catch-plate in said casing, having a forwardly-projecting portion which extends into and through the opening in the front 5 piece of the casing, an upwardly and forwardly extending finger-piece on said portion of the catch-plate, a rearwardly-projecting portion on said catch-plate which extends into and through the opening in the back o piece of said casing, and means on said rearwardly-projecting portion for engagement with the other frame-section of the bag or purse frame, substantially as and for the purposes set forth.

15 2. In a bag or purse frame, the combination, with a pair of hinged or pivoted frame-sections, of a lock or catch on one of said frame-sections, comprising a casing secured upon the frame-section, provided with a front and 20 back piece, each piece having an opening therein, a holding or locking catch-plate in said casing, consisting, essentially, of a main body portion, and oppositely-projecting lugs or projections thereon, all arranged between 25 the inner surfaces of said front and back pieces to prevent lateral displacement, a forwardly-projecting portion on said body portion of the catch-plate which extends into and through the opening in the front piece of 30 the casing, an upwardly and forwardly extending finger-piece thereon, a rearwardly-projecting portion on said catch-plate which extends into and through the opening in the back piece of said casing, a nosing on said 35 rearwardly-projecting portion, for holding engagement with the other of said frame-sections, and a spring in said casing bearing on said main body portion of the catch-plate, substantially as and for the purposes set forth.

40 3. In a bag or purse frame, the combination, with a pair of hinged or pivoted frame-sections, of a lock or catch secured upon one of the frame-sections, comprising, a casing, consisting, essentially, of an upwardly-curved top, a front piece having an opening therein, and a back piece having an opening therein, lugs at the opposite ends of said curved top for securing said casing on said frame-section, a catch-plate in said casing, having a locking or holding portion extending into and through the hole in said back piece, a forwardly-projecting portion extending into and through the opening in said front piece, a spring in said casing, arranged over the main 45 body portion of said catch-plate and having its ends in holding engagement with the inner surface of the curved top of said casing, and a finger-piece on said forwardly-projecting portion of said catch-plate for raising the locking or holding portion of said catch-plate by means of a downward pressure on said finger-piece, against the action of the said spring, substantially as and for the purposes set forth.

45 4. In a bag or purse frame, the combination, with a pair of hinged or pivoted frame-sec-

tions, of a lock or catch on one of said frame-sections, comprising, a casing, consisting, essentially, of an upwardly-curved top, a front piece having an opening therein, and a back piece having an opening therein, lugs at the opposite ends of said curved top for securing said casing on said frame-section, a catch-plate in said casing, a pair of oppositely-arranged lugs or ears on said catch-plate arranged between said front and back pieces of the casing to prevent lateral displacement, a locking or holding portion extending into and through the opening in said back piece, a forwardly-projecting portion extending into and through the opening in said front piece, a spring in said casing, arranged over the main body portion of said catch-plate and having its ends in holding engagement with the inner surface of the curved top of said casing, 85 and a finger-piece on said forwardly-projecting portion of said catch-plate for raising the locking or holding portion of said catch-plate by means of a downward pressure on said finger-piece against the action of the said spring, substantially as and for the purposes set forth.

5. In a bag or purse frame, the combination, with a pair of hinged or pivoted frame-sections, of a lock or catch on one of said frame-sections, comprising, a casing, having an opening in its side, and a spring-actuated holding or locking catch in said casing, provided with a portion extending into and through said opening and having a fulcrumal bearing upon the upper surface of one of said frame-sections, outside and independent of the lock or catch casing, substantially as and for the purposes set forth.

6. In a bag or purse frame, the combination, with a pair of hinged or pivoted frame-sections, of a lock or catch on one of said frame-sections, comprising, a casing, consisting, essentially, of a top piece, a front piece having an opening therein, and a back piece having an opening therein, a spring in said casing, a catch-plate in said casing having a portion arranged directly beneath said spring, a locking or holding portion on said catch-plate extending into and through said opening in the back piece for engagement with the other frame-section, and a forwardly-projecting portion extending into and through said front piece of the casing, provided with a finger-piece, and having a fulcrumal bearing upon the upper surface of the frame-section to which the lock or catch casing is secured, outside and independent of said casing, substantially as and for the purposes set forth.

7. In a bag, or the like, the combination, with the side piece *a* and a pocket *b*, of a frame secured thereto, consisting, essentially, of a frame-section *c* and securing-plate *d* between which portions of the piece *a* and the pocket *b* are arranged, and rivets or pins *d* for securing said parts together and the frame-section *c* in position, a second frame-section

e hinged to said frame-section *c*, an inlay *h* between which and the frame-section *e* other portions of the side piece *a* and the pocket *b* are placed, and rivets or pins *i* for securing said parts together and the frame-section *e* in position, substantially as and for the purposes set forth.

In testimony that I claim the invention set forth above I have hereunto set my hand this 18th day of September, 1900.

ALBERT F. FULLER.
